UNITED STATES PATENT OFFICE.

FERDINAND J. TILLMAN, OF ST. LOUIS, MISSOURI.

HAIR-CUTTING DEVICE.

1,393,053.

Specification of Letters Patent.

Patented Oct. 11, 1921.

Application filed June 12, 1919. Serial No. 303,807.

To all whom it may concern:

Be it known that I, FERDINAND J. TILLMAN, a citizen of the United States of America, a resident of the city of St. Louis, State 5 of Missouri, have invented certain new and useful Improvements in a Hair-Cutting Device, of which the following is a specification.

The primary object of this invention is to provide a hair cutting device containing a comb and a cutting blade; said cutting blade being normally held out of alinement for cutting engagement with said comb by spring tension so as the comb can be used to hold the hair in position for cutting without being interfered with in any way by the cutting blade, there being a guide to bring the cutting blade in cutting alinement with the comb, when so desired.

Another object of the invention is to provide means for an interchangeable cutting blade and an interchangeable comb.

Another object of the invention is to provide means for moving said cutting blade and comb into a position to be used independently of each other; that is, the cutting blade can be used for shaving and the comb can be used for combing the hair, without one interfering with the other when so desired.

Other and further objects of this invention will appear in this specification and will be pointed out in the appended claims, reference being had to the accompanying drawings.

Figure 1 is a front view showing the hair cutting device being held apart by the spring shape handles.

Fig. 2 is a front view showing the device closed in resistance to the spring shape handles.

Fig. 3 is a side view of Fig. 1 of the hair cutting device showing the comb and the cutting edge held out of cutting alinement.

Fig. 4 is a side view of Fig. 2 showing the comb and the cutting blade forced into cutting alinement.

Fig. 5 is a section taken on line V—V of Fig. 2 showing the comb and cutting edge forced into cutting alinement by the guide.

Fig. 6 is a view of the cutting device moved in an open position so as to be used independently but with the comb and cutting blade removed.

Fig. 7 is a side view of Fig. 6, partly broken away, showing the parts that hold the razor blade in place.

Fig. 8 is a razor blade removed from the cutting device.

Fig. 9 is a section view taken on IX—IX of Fig. 8.

Fig. 10 is a comb removed from the handle.

Fig. 11 is a section view taken on line XI—XI of Fig. 10.

Fig. 12 is a top view of Fig. 6, partly broken away, showing where the comb is placed.

Fig. 13 is a top plate for holding the comb in place.

Fig. 14 is a side view of the top plate shown in Fig. 13.

Fig. 15 is a top view of the guide for guiding the cutting blade into alinement for cutting.

Fig. 16 is a side view of the guide shown in Fig. 15.

Figs. 17 and 18 are the screws for holding the comb to said handle.

Referring to the drawings, 1 designates a spring steel handle containing a rounded spring end 2, and loosely pivoted at 3 to another spring steel handle 4 that is rounded at 5 and containing an end 6 that butts against a pin 7 on the handle 1. These spring handles are so shaped that they normally have a tendency to force open through their curve spring ends 2 and 5 as shown in Fig. 1 and also have a tendency to be forced out of alinement as shown in Fig. 3, but they are held in position as shown in Fig. 1 and Fig. 3 by guide 8 that is loosely pivoted at 9 to the handle 1 and contains a stopping abutment 10 for limiting the outward movement of the handle 4. This guide 8 is held in the position as shown in Fig. 1 by spring 11 that fastens to a stud 12 one the guide 8 and a stud 13 on the handle 1. This spring has a tendency to hold the guide against a pin 14 on handle 1, but is adapted to be swung into the position shown in dotted lines of Fig. 1 when not in use, so that spring 11 will hold it against the pin 15. The upper end of the handle 1 has a thinner end 16, against which the comb 17 is adapted to be set. 18 is a plate that is adapted to be set over the comb 17, and 19 and 20 are screws

that fit loosely through the holes 21 and 22 of the plate 18 and fits loosely through the holes 23 and 24 of the comb 17 and are adapted to screw through the threaded holes 25 and 26 of the handle 1, thereby securely holding the comb against said handle.

On the upper end of handle 4 is a depressed

space 27 in which the cutting blade 28 may fit. 29 is a short pin over which the hole 30 in the blade 28 may fit. 31 is a longer pin which loosely fits through the hole 32 of the 5 cutting blade and also through the hole 33 of the cover plate 34. This cover plate 34 is loosely pivoted at one end by a screw 36 to the handle 4. Under the screw 36 is a spring 37 that has a tendency to hold the 10 plate 34 flat against the handle 4. It will be seen that if the blade 28 is set in the depressed space 27 and the cover plate 34 is swung into the position as shown in Fig. 1, the spring 37 will have a tendency to force 15 the pin 31 through the hole 33, and thereby holding the cover plate 34 flat against the upper part of the handle 4 and thereby hold the blade 28 in position. 38 is a small extension of cover plate 34 used for lifting the 20 hole 33 in the plate 34 off the pin 31, when it is desired to move the plate 34 into position shown in Fig. 6 for the purpose of removing the razor blade. A is a holding arm that is also pivoted at 3, having a stud 39 25 on which a spring 40 is attached. The other end of spring 40 is fastened to a stop-stud 41 on handle 1. This holding arm A can be operated with the thumb and pushed up against the plate 18, after the comb has positioned the hair the proper length for cutting and thereby the holding arm A holds the hair against the plate 18 while the cutting blade 28 cuts the hair.

What I claim is—

35 1. In a hair cutting device a movable cutting edge, a movable comb, said cutting edge adapted to be moved out of traveling cutting alinement from said comb, and a guiding member extending from said comb to 40 said cutting edge.

2. The combination in a cutting device containing a detachable comb and a detachable cutting blade; said comb and said blade adapted to be swung in close proximity for 45 cutting engagement, but said comb and said blade normally held out of cutting alinement and a guide for guiding them into proper alinement.

3. A combination in a cutting device containing a comb and a razor, their handles 50

being pivotally mounted and each adapted to be used independently of the other and a guide for bringing them into proper cutting alinement so that they may be used in unison.

55

4. The combination of a cutting device containing two spring tension handles; one handle carrying an interchangeable comb, and the other handle carrying an interchangeable razor; said comb and said razor 60 adapted to be used independently of each other and a guide for guiding said razor into cutting alinement with said comb.

5. The combination in a cutting device containing a comb and a razor; said comb 65 and razor adapted to be brought into cutting relation with each other and a guide for limiting the distance that they may be brought out of cutting relation and means for disconnecting them from said guide so that the comb and the razor may be used independently without interference from the 70 guide or the spring tension.

6. In a hair cutting device, the combination of a blade, a comb and a holding arm, 75 said holding arm being movable and adapted to hold the hair against the comb during the cutting action of said blade.

7. In a cutting device the combination of 80 a comb, a cutting blade normally held out of traveling cutting alinement with said comb, and means coöperable with said cutting blade and said comb for bringing the cutting blade into cutting alinement.

8. In a hair cutting device, a holder bearing an interchangeable blade, a comb coöperable with said blade, means provided whereby said blade is normally held out of cutting alinement with said comb, and other 90 means for bringing said blade into cutting alinement.

9. In a hair cutting device, a holder bearing an interchangeable blade, a comb coöperable with said blade, means provided whereby said blade is normally held out of cutting alinement with said comb, other means for bringing said blade into cutting alinement, and a hair holding device coöperable with said blade and said comb.

FERDINAND J. TILLMAN.
